UNITED STATES PATENT OFFICE

2,001,728

ROCK DRILLING MOTOR

Mervin Chester Huffman, Claremont, N. H., assignor to Sullivan Machinery Company, a corporation of Massachusetts

Application June 23, 1932, Serial No. 618,924

6 Claims. (Cl. 121—10)

My invention relates to rock drilling motors, and more particularly to rock drilling motors of the type employed for the drilling of fairly deep, dry holes from which it is desired to blow the 5 cuttings.

An object of my invention is to provide an improved drilling motor of the type specified. Another object of my invention is to provide an improved hole blowing apparatus for use with rock 10 drills, which will involve a minimum of change from a standard motor construction in which the facilities for this operation are not present. A further object of my invention is to provide 15 an improved rock drilling mechanism in which the hole blowing operation may be controlled readily by a hand close to the normal drill throttle operating devices. Other objects and advantages of the invention will hereinafter more fully appear.

20 In the accompanying drawing, in which a preferred form of my invention is shown for purposes of illustration,—

Fig. 1 is, in the main, a central longitudinal vertical section through a rock drilling motor in 25 which the preferred embodiment of my invention is incorporated, some parts of the motor being shown in elevation, and the parts being shown in the position for hole blowing.

Fig. 2 is a fragmentary view showing the same 30 motor with the parts in one of the normal running positions.

Fig. 3 is another fragmentary view showing the 35 distributing valve mechanism in a different running position.

Fig. 4 is an enlarged fragmentary sectional view 40 taken on the plane of Fig. 2, showing the distributing valve in hole blowing position.

The illustrated form of tool is provided with a cylinder 1 which is embraced at its rear end 45 by a head block or casing 2, on which a handle 3, having suitable grasping portions 4, is mounted. At the forward end of the cylinder there is provided a chuck 5 which is adapted to receive the shank or head of a drilling tool 6, the inner end 50 of this shank being positioned to receive blows from a hammer piston 7 which is reciprocable within the cylinder. The hammer piston is actuated by pressure fluid controlled by a pressure fluid actuated distributing valve 8, which is of 55 the type thrown in one direction by constant pressure and in the opposite direction by a piston controlled reduced pressure. The valve 8 is herein located in alinement with the piston and at the rear end thereof, within a valve chamber formed in a valve block 9 which is seated in the casing 2.

Between the valve block and the cylinder there is provided a plate 10 having a rearwardly projecting boss 11.

Pressure fluid is conducted to the tool from any suitable source, through a supply pipe 12 and through a throttling device herein comprising a valve 13, later more fully described, at the rear end of the valve block. At its rear end the valve chamber communicates with a constant pressure chamber 14 to which, through an opening 15, 10

pressure is supplied so long as the throttle valve 13 is unseated. The communication of the valve chamber with the constant pressure chamber 14 is through an opening of reduced cross sectional area, and the valve has a contracted portion 15' 15 slidably in the opening and constantly exposed to live pressure fluid in the constant pressure chamber. The valve chamber is provided also with a constant pressure groove 16, to which the live pressure fluid is constantly admitted, when the 20 throttle is open, through one or more longitudinal passages 17, the latter extending from the groove rearwardly to the space to which the throttle valve admits pressure. In the rear position of the distributing valve, working pressure is conducted from the pressure groove 16 to the forward 25 end of the cylinder to return the piston, by way of a circumferential valve groove 17', and one or more longitudinally extending passages 18, which open into the forward end of the cylinder through 30 ports 19. In the forward position of the distributing valve, working pressure fluid is conducted to the rear end of the cylinder from the pressure groove 16, through the circumferential valve groove 17' on the distributing valve, to a valve 35 block groove 20, and thence forwardly through the longitudinal passage or passages 21 to the rear end of the cylinder. Exhaust is effected from the rear end of the cylinder when the distributing valve is in its rearward position, through the 40 passages 21, the valve block groove 20, an exhaust valve-groove 24, an exhaust passage 25, an exhaust space 26 in the member 2, and a terminal exhaust passage 27. From the forward end of the cylinder exhaust takes place in part through a 45 bore 28, which is closed by the striking portion 29 of the piston, when the latter is in forward position, and through the bore of the drill steel, and around the latter; and also, in part, through port 19, passage 18, and passages 30 communicating 50 at their opposite ends with the rear end of the main valve chamber and with the space 26, respectively. When the piston 7 is in its forward position, the reduced portion 29 fills the opening 55 28 and prevents the escape of air from the for-

ward end of the cylinder, so that air admitted through the port 19 will force the piston rearwardly. However, as soon as the portion 29 is withdrawn from the bore 28, the forward end of the piston is connected for a restricted exhaust through the bore 28 and that in the hollow drill steel.

The distributing valve is reciprocated by differential pressure, means being provided for intermittently applying pressure fluid to the forward or larger area of the valve to lift it intermittently against the constant pressure in the pressure chamber 14. For this purpose, the valve is constructed in the form of a hollow shell, the interior of which is partially filled by the plug 11, previously mentioned, the latter having a groove or passage 32 formed in its side connecting with an intermittent pressure passage 33. The passage 33 is connected by two ports 34 and 35, opening 15 into the cylinder chamber at different points spaced from each other longitudinally of the cylinder, with the cylinder bore; the port 34 being substantially in the same transverse plane as a second port 36, which is in constant communication with the constant pressure chamber 14 through a longitudinal passage 37. When the piston moves forwardly, the port 34 is connected with the constant pressure port 36 by means of a reduced portion 38 on the piston, and the valve 20 is reversed by pressure admitted to the large area thereof from the constant pressure chamber through ports 36, 34 and passage 33. On the other hand, when the piston moves backward, pressure fluid is exhausted from the larger area 25 of the valve by the piston's uncovering of the port 35 and connecting the latter to exhaust through the bore 28 and the hollow steel; a sufficient pressure drop following, during normal running, the withdrawal of nose 29 from bore 28 to permit constant pressure on the reduced upper end of the valve to overcome the piston controlled reduced pressure below the valve.

Through the reciprocation of the distributing valve and the transfer of pressure fluid through the described ports and passages, the hammer piston is caused to move reciprocatively within the cylinder and to deliver its blows against the head of the tool with great rapidity, in a manner which will be obvious from the description given.

To enable the blowing of the hole being drilled, which may advantageously be accomplished by holding the piston 7 at the rear end of the cylinder by supplying pressure continuously to the forward end of the cylinder and permitting the pressure to pass from said forward end through the hollow drill steel, I have provided improved mechanism.

Within a bore 40, extending from end to end of the valve block 9, is reciprocably arranged a manually operable valve member 41. This valve member has a push button portion 42 which projects through an opening 43 in the member 2 into convenient reach of an operator. It also has a shoulder forming collar 44 movable in an enlarged chamber 45 in the member 2 adjacent the top of block 9 and limiting movement of the valve member 41 in each direction. The lower end of the bore 40 is in communication, through a recess 46, with the space below and within the valve member 8.

Valve member 41 has a circumferential groove 47 and also a longitudinally extending bore 48 extending from the lower end of the member to a point high enough to permit communication through a radial port 49 with the groove 47.

The bore 40 is so related to the grooves 16 and 20 that it cuts into both of them, with the construction shown, but the opening of the bore 40 into groove 20 is immaterial, since valve member 41 always closes communication; and if desired the parts might be proportioned to avoid the opening of bore 40 into groove 20. The groove 47 communicates with groove 16 when the valve 41 is depressed to the position shown in Fig. 1, and conducts fluid from the latter to port 49, through which it passes to bore 48 and recess 46 and beneath the valve 8, overcoming the opposing constant pressure and holding the valve in raised position, thereby causing the piston 7 to be maintained continuously in rearward position and fluid to flow to the hollow drill steel from the front end of the cylinder bore. It will be observed that fluid flows not only by way of 17, 16, 18 and 19, but also by way of 17, 16, 47, 49, 48, 46, 33 and 35 to the forward end of the cylinder, the pressure drop with the port 35 uncovered not being sufficient to permit valve 8 to move to its bottom position so long as the relatively direct supply through 16, 47, 49, 48 and 46 continues.

When the push button 42 is released, the pressure below valve 41 will raise the valve to the position shown in Fig. 3, interrupting communication between groove 47 and live air groove 16. The distributing valve 8 will then be free to resume normal operation and cause the piston 7 to resume hammering. A spring may obviously be used below the valve 41 to hold it in top position, if desired, but since the pressure below the valve 8 never drops to atmospheric during running of the motor, the valve 8 will be held up without this added aid.

A suitable hand lever 50 is arranged to open the throttle valve 13 when desired. Of course the latter must be open during hole blowing.

Extended repetition of the mode of operation is not necessary. To start the drill motor, the operator depresses the outer end of lever 50 and moves the throttle valve 13 to the left and admits air from the bore 12 to the space 15, and the motor starts. To blow the hole, the operator depresses the plunger or push button 42 and moves the valve 41 to the position of Fig. 1, and live air then flows from space 15 through passages 17 to groove 16, then through groove 47, port 49 and bore 48 to recess 46, and holds valve 8 in top position. Live air then flows from space 15, through passages 17, groove 16, groove 17', passages 18 and port 19 to the bottom of the cylinder, and holds piston 7 in the position of Fig. 2, and also flows in part through the hollow steel to blow the hole. Simultaneously with this flow through 18, there is a supplemental flow through 33 as above explained. Release of plunger 42 while the throttle 13 is kept open will cause a resumption of hammering.

From the foregoing description, it will be apparent that I have provided an improved drilling apparatus having improved hole blowing means, which is very simple, which provides surety of action by subjecting a large area of the distributing valve to live pressure, which requires a minimum of modification of the familiar type of drill with which it is used, and which is exceedingly convenient to operate.

While I have in this application specifically described one form which my invention may assume in practice, it will be understood that this form is shown for purposes of illustration, and that the invention may be modified and embodied in

various other forms without departing from its spirit or the scope of the appended claims.

What I claim as new and desire to secure by Letters Patent is:

- 5 1. A pressure fluid motor comprising a cylinder having a bore, a piston therein, a fluid actuated distributing valve controlling the movement of said piston, said valve having an area subjected to constant pressure and a larger opposed area subjected to a piston controlled reduced pressure, a passage connecting said last named area to the cylinder bore, said passage controlled by said piston and provided to supply pressure fluid from said cylinder to said larger area to throw said valve against the opposing constant pressure, and means for interrupting operation of said valve to hold said valve in its thrown position against said opposing constant pressure and to hold said piston retracted including means for supplying live fluid to said larger area continuously, said passage when said valve is in said thrown position conducting a portion of the fluid supplied continuously to said larger area from the latter to the cylinder bore. 10
- 10 2. A pressure fluid motor comprising a cylinder having a bore, a piston therein, a fluid actuated distributing valve controlling the movement of said piston, said valve having an area subjected to constant pressure and a larger opposed area subjected to a piston controlled reduced pressure, a passage connecting said last named area to the cylinder bore, and means for interrupting operation of said valve and normal operation of the piston including means for supplying live pressure fluid to said larger area continuously and thence through said passage to the cylinder bore. 15
- 15 3. A pressure fluid motor comprising a cylinder having a bore, a piston therein, a fluid actuated distributing valve controlling the movement of said piston, said valve having an area subjected to constant pressure and a larger opposed area subjected to a piston controlled reduced pressure, a passage controlled by said valve for supplying piston actuating fluid to one end of the cylinder bore, a passage connecting said larger area to the cylinder bore, and means for interrupting operation of said valve and normal operation of the piston including means for supplying live fluid to said larger area continuously and thence through said second named passage to the cylinder bore, pressure fluid continuously flowing through said supply passage to said end of said cylinder bore when operation of said valve is so interrupted. 20
- 20 4. A pressure fluid motor comprising a cylinder having a bore, a piston therein, a fluid actuated distributing valve controlling the move- 25
- 25 ment of said piston, said valve having an area subjected to constant pressure and a larger opposed area subjected to a piston controlled reduced pressure, a passage connecting said last named area to the cylinder bore, and means for interrupting operation of said valve and inter- 30
- 30 rupting normal piston operation including a hollow, manually operable valve having a longitudinally extending passage for supplying live pressure fluid to said larger area continuously and thence through said passage to said cylinder bore. 35
- 35 5. A pressure fluid motor comprising a cylinder having a bore, a piston therein, a fluid actuated distributing valve controlling the movement of said piston, said valve having an area subjected to constant pressure and a larger opposed area subjected to a piston controlled reduced pressure, a passage connecting said last named area to the cylinder bore, and means for interrupting operation of said valve and inter- 40
- 40 rupting normal piston operation including a hollow, manually operable valve having a longitudinally extending passage for supplying live pressure fluid to said larger area continuously and thence through said passage to said cylinder bore. 45
- 45 6. A pressure fluid motor comprising a cylinder, a piston therein, a fluid actuated distributing valve controlling the movement of said piston and having an annular groove on its exterior periphery, said valve also having an area subjected to constant pressure and a larger opposed area subjected to a piston controlled reduced pressure, a fluid supply passage, a passage for conducting live pressure fluid from said supply passage to the cylinder bore, the groove in said valve when said valve is in one position connecting said passages, and means for interrupting operation of said valve to maintain said passages in constant communication including means for supplying live pressure fluid from said supply passage independently of said valve groove to said larger area continuously. 50
